Primary Examiner — Richard A Edgar*Assistant Examiner* — Carolyn W Davis(74) *Attorney, Agent, or Firm* — Tucker Ellis LLP;
Michael G. Craig(57) **CLAIM**

The ornamental design for a ventilating fan, as shown and described.

DESCRIPTION

FIG. 1 is a rear view of a ventilating fan, illustrating our new design;

FIG. 2 is a right side view thereof;

FIG. 3 is a left side view thereof;

FIG. 4 is a top view thereof;

FIG. 5 is a perspective front view thereof;

FIG. 6 is a front view thereof; and,

FIG. 7 is a perspective view thereof.

The broken lines show portions of the ventilating fan which form no part of the claimed design.

1 Claim, 7 Drawing Sheets(56)
